UNITED STATES PATENT OFFICE.

OGDEN MINTON, OF GREENWICH, CONNECTICUT.

VELOCITY FLUID VACUUM SEAL, METHOD, AND APPARATUS.

Application filed November 30, 1920, Serial No. 427,436. Renewed February 17, 1926.

My invention relates to the method of treating materials in a vacuum, and more particularly to the method of protecting the opening or openings into the vacuum chamber, through which opening or openings the material to be treated is introduced and withdrawn from the chamber.

My invention relates more particularly to a vacuum seal maintained by the application of velocity head, i. e. the difference in pressure between the atmosphere and vacuum being balanced by the velocity head of the sealing medium. Through this seal the material to be treated in the vacuum chamber is passed in any suitable manner.

My invention further relates more particularly to the method of drying sheet material, as a continuous web of paper either coming from the wet end of a paper machine, or from a sizing vat, or from a coloring apparatus, coating machine or printing machine or directly from a roll of wet paper.

My invention further relates to a vacuum apparatus including a vacuum chamber having passages extending from the said vacuum chamber and open to the atmosphere. These passages are protected by velocity fluid seals which prevent the admission of air into said vacuum chamber as the material to be treated is introduced and withdrawn through said seals.

My invention further relates to employing any suitable fluid, in the velocity seals, which has no affinity for or deleterious effect upon the material to be treated in the vacuum chamber. I may for example use mercury or an amalgam, or air, or steam or water or similar fluid having the characteristics above stated. In the case of water, if the material to be treated should, for example, be a web of paper to be dried I may protect the web by endless rubber or water proof felts or other similar guards.

My invention further relates to employing passages having restricted areas merging into progressively larger areas between the atmosphere and the interior of the vacuum chamber, forming in effect Venturi nozzles, through which the fluid of the velocity fluid seals flows.

My invention further relates to such restricted passages in combination with a barometric seal and a pump; or restricted passage and Venturi type nozzle in combination with a pump to force the liquid of

the seal through the Venturi nozzle; or a combination of the two forms just described; or a plurality of nozzles opening into a single Venturi type of nozzle in combination with a barometric seal; or any combination of these different instrumentalities, or their equivalents.

My invention further relates to collecting the fluid of the velocity fluid seal and again using it in the seal, or if the fluid is steam, collecting and using it in the dryers; or using it to heat the building; or I may condense it or otherwise dispose of it.

My invention further relates to certain steps and combinations of steps, also to certain elements and combinations of elements, whereby the method or processes herein described may be carried out, as well as to certain details of construction, all of which will be more fully hereinafter described in the specification and pointed out in the claims.

I have shown in the drawings, different forms of apparatus which may be used to carry out my improved method, but it is to be distinctly understood that my invention is not to be confined to the particular form of apparatus, shown by way of illustration.

In the accompanying drawings the same reference numerals refer to similar parts in the several figures.

Fig. 1 is a vertical section through a vacuum chamber equipped to dry sheet material, as for example, a web of paper, and with two different types of my velocity fluid vacuum seals;

Fig. 2 is a vertical section, on an enlarged scale, of a detail of the type of velocity fluid vacuum seal, shown on the left of Fig. 1;

Fig. 3 is a vertical section on an enlarged scale of a detail of the type of velocity fluid vacuum seal shown on the right of Fig. 1;

Fig. 4 is a detail vertical section of another modified form of my invention;

Fig. 5 is a vertical section of still another modification in which a plurality of nozzles are employed;

Fig. 6 is a vertical section of still another modification in which a plurality of nozzles are employed connected in series;

Fig. 7 is a diagrammatic view of the simplest form of my invention;

Fig. 8 is a vertical section on an enlarged scale, showing a modification of my inven-

tion in which the seal is arranged at an angle to the horizontal to obtain more or less static head.

I will describe the simplest form of my invention first, that shown diagrammatically in Fig. 7.

The vacuum chamber 100 has a vacuum maintained therein in any suitable manner by connecting the pipe 101 with any suitable 10 exhausting apparatus. This vacuum chamber has two passages 102, 102 open to the atmosphere. Through these passages the material to be treated in the vacuum chamber 100 is introduced and withdrawn. Of course if the passages were left unguarded the vacuum in the vacuum chamber 100 would be broken.

My invention broadly consists in guarding the passages to the atmosphere by velocity fluid vacuum seals, the velocity of the fluid being sufficiently high to prevent any air working past the velocity seal into the vacuum chamber.

In my invention suitable material may be 25 introduced into and withdrawn from the vacuum chamber 100 through my velocity fluid seals 103, 103. It may be treated in any suitable manner within the vacuum chamber 100. It may be fed through the 30 vacuum chamber continuously or not. I have shown by way of example the material in the form of a continuous web 7 which passes continuously through the vacuum chamber 100 and the velocity fluid vacuum 35 seals 103, 103. This web 7 may be dried in the vacuum chamber, or coated, impregnated or treated in any other suitable manner, and may be fed into and out of the vacuum chamber in either direction as indicated 40 by the arrows.

These passages 102, 102, have restricted areas 104, 104. Connected with these restricted areas are nozzles 105, 105. The area of the passages 102, 102 increases at 106, 106 45 adjacent the restricted areas 104, 104.

Fluid which has no affinity for or deleterious effect upon the web 7, or other material treated, is forced into the chamber 107, 107 and through the nozzles 105, 105 at sufficient velocity to prevent air passing through the restricted area 104 and getting into the vacuum chamber 100. The velocity required will depend on the vacuum maintained in the vacuum chamber and the fluid used for the seal. Preferably I employ as near a perfect vacuum as I can maintain; usually about 28 inches of mercury.

Whatever fluid is used passes through the nozzles 105 with comparatively high velocity. As the fluid reaches the portion 106 of comparatively large area its velocity is reduced. The passage 102 with its restricted area 104, nozzles 105 and portions of greater area 106 is in effect a Venturi type nozzle. 65 The passage 102 is of course wide enough to

permit the free passage of the widest web or other material to be passed into and out of the vacuum chamber 100.

The fluid which I employ for my velocity fluid vacuum seal may be mercury or an 70 amalgam or similar material, steam, water, air or similar fluid. If water is used as the fluid and the material treated is a web 7 of paper to be dried, then I may protect the upper and lower surface of the web by rubber or other waterproof endless felts.

If air is used as the fluid of the seal it will be permitted to pass into the atmosphere. If water be used it may be collected in the chamber 108 and drawn off by the pipe 109 80 to be used again or allowed to run to waste. If mercury or amalgam be used it would be collected in the chamber 108 and pass through the pipe 109 to be used again as shown, for example, in the other figures of the drawings. If the fluid be steam it would pass from chamber 108 through the pipe 109 to be used as the heating medium in the steam drying cylinders or drums shown in the other figures of the drawings, or it may 85 be used to heat the building, or the pipe 109 may be connected to a vacuum pipe or condenser.

My invention is particularly adapted to be 90 used in connection with drying sheet material in the form of paper, though it is to be distinctly understood that it is equally applicable to and covers drying sheet material in the form of textile fabrics, as for example, drying such fabrics after they have been washed or bleached or dyed, or otherwise treated by a liquid of some description.

I have shown my invention in connection 95 with drying a web of paper in the other figures of the drawings.

In these other figures 1 is a vacuum chamber in which I mount a plurality of drying drums or cylinders 2, 3, 4, 5 and 6. The wet web of paper 7 coming directly from the wet end of a paper machine, or from a coloring apparatus, coating machine, printing machine, or directly from the roll of wet paper, is fed to the vacuum chamber 1 from the left of Fig. 1 in the direction indicated 100 by the arrows. It is preferably, though not necessarily, received between the upper traveling felt 8 and the lower traveling felt 9. These felts 8 and 9 with the interposed wet web of paper 7 pass under the felt roll 10 in the felt roll chamber 11, through the seal 12 in said felt roll chamber, thence through the restricted passage 13, and into the interior of the vacuum chamber 1. The web is then dried while it passes over the drying drums or cylinders 2, 3, 4, 5 and 6.

I may not employ felts. When I do use them I preferably arrange them as shown in Fig. 1.

The upper felt 8 passes over the first drying drum or cylinder 2, then over the dry-

ing drum or cylinder 3, around the guide rolls 15, 16 over the rotating felt dryer 17, guide roll 18, drying drums or cylinders 5, and 6 and under the second felt roll 19, 5 mounted in the second velocity fluid seal, thence on the exterior of the machine, back to the first felt roll 10 as shown by the arrows.

The lower felt 9, after passing under the 10 felt roll 10, passes around the periphery of the drying drum or cylinder 2, over the guide rolls 20, 21, around the felt dryer 22, over the guide roll 23, drying drum or cylinder 4, guide roll 24, felt dryer 25, 15 guide rolls 26 and 27, around the periphery of the drying drum or cylinder 6, under the felt roll 19, over the guide roll 28, and thence under the machine back to the guide roll 29 and again under the felt roll 10.

20 Among other objects of my present invention is the reduction to a minimum of the amount of fluid, as for example, mercury amalgam or similar material, which I may employ for the velocity fluid vacuum seals 25 of the vacuum chamber; also to reduce the level of the fluid within the vacuum chamber, and also, in some cases, to prevent the fluid getting into the vacuum chamber at all.

30 By my invention I reduce the height of the mercury in the vacuum chamber in contact with the drying drums or cylinders 2 and 6 and thereby make them substantially as efficient as the other drying drums or 35 cylinders 3, 4 and 5.

It is to be understood that when mercury or similar material, is placed within the 40 chambers 11 and 14, it would flow through the restricted passages 13, 13 and would rise in the vacuum chamber 1 to a height 45 dependent upon the degree of vacuum maintained in said chamber. In a perfect vacuum it would rise 30 inches within said chamber, the difference being the difference between the atmospheric pressure on the 50 mercury within the chamber 11 and the lack of pressure in the perfect vacuum maintained within the vacuum chamber.

55 In my invention I approach as near a perfect vacuum as possible, usually employing a vacuum of about 28 inches of mercury. With such a vacuum in the vacuum chamber 1 there would be 28 inches of mercury in said chamber in which the drying drums or cylinders 2 and 6 would be immersed. This 60 immersion requires a comparatively large quantity of mercury, or other similar fluid.

65 By my invention I use velocity fluid seals to compensate for the difference in pressure between the atmosphere and vacuum in the chamber. In this manner I can prevent any fluid of the seals working into the vacuum chamber; or, I may regulate the amount of fluid as mercury, or similar material of the seal which will flow into the vac-

uum chamber. This permits me to regulate the height of the fluid of the velocity fluid seal within the vacuum chamber, regardless of the degree of vacuum maintained within said chamber. That is, I can so regulate 70 the velocity of the fluid seal that no fluid will enter the vacuum chamber; or, I can so regulate the velocity that only a very small portion will enter the vacuum chamber. This insures that the periphery of the 75 drying drums 2 and 6 will be free of the fluid of the seal; or immersed in the fluid to a very small extent, the degree of immersion being subject to regulation. Should any of the fluid of the velocity seal find its way 80 into the vacuum chamber it can be drawn off by the barometric seal without substantially interfering with the drying action of the drying cylinders or drum 2.

In Fig. 1, on the left of said figure, I 85 have shown one form of apparatus to regulate the level of the fluid of the velocity fluid seal in the vacuum chamber. On the right of said Fig. 1, I have shown another form of my invention, and in Figs. 4, 5, 6 90 and 8 I have shown still other modifications of my invention.

In connection with the velocity fluid seal shown on the left of Fig. 1, and on an enlarged scale in Fig. 2, the fluid, as for example, mercury, or other fluid is placed in the felt roll chamber or housing 11. Atmospheric pressure will cause the mercury in the felt roll housing to reach the level 29. 100 It would then pass through the restricted area 13, into the larger area 36, and thence 105 into the vacuum chamber 1. It would rise on the periphery of the drying drum 2 to a height dependent upon the degree of 110 vacuum maintained in the vacuum chamber. In a perfect vacuum it would rise 30 inches. In the vacuum which I usually employ, about 28 inches, it will rise 28 inches, making the drying drum or cylinder 2 revolve in a depth of about 28 inches of mercury. This requires an unnecessary amount of 115 mercury.

In this form of my invention I employ a barometric seal 30. The pipe 31 of this seal is connected at 32 with the vacuum chamber. The height of the barometric seal may vary. The suction pipe 33 of the pressure pump 34 is connected to the barometric seal and takes mercury, or similar 120 fluid sealing medium, from the barometric seal and forces it into the felt roll chamber 11 under the felt roll 10. The pump is operated in any suitable manner as by means of the motor 35. The atmospheric 125 pressure upon the mercury, or similar material, in the felt roll chamber 11 will cause the mercury to flow through the restricted passage 13. The mercury then flows into the vacuum chamber 1, and, in this form of 130 my invention, in contact with a small por-

tion of the periphery of the drying drum or cylinder 2, and thence back into the barometric seal 30. The pump 34 should be regulated so as to just supply sufficient liquid to keep the mercury or similar material at the level 29 as indicated in Figs. 1 and 2. Should for any reason the pump be operated at such a speed as to cause the mercury to back up in the felt roll housing 11, the surplus fluid will pass out through the overflow 37 back to the barometric seal 30. To prevent any air getting into the vacuum chamber 1, I locate the end 38 of the pipe 31 in the barometric seal 30, below the level of the suction pipe 33 of the pump, so that even if the pump should accidentally and momentarily operate at too great a speed, it cannot reduce the level of the liquid in the barometric seal sufficient to admit air into the vacuum chamber through the pipe 31. In this form of my invention, the parts are so located and operated that only a very small portion of the periphery of the dryer 2 will be immersed in the mercury or similar material, as shown in Figs. 1 and 2. In this form of my invention I use the restricted passage 13, but, preferably, no Venturi type nozzle as in the other forms.

On the right of Fig. 1, and on an enlarger scale in Fig. 3, I have shown a different form of velocity fluid vacuum seal. In this form of my invention the restricted passage 13 is connected with nozzles 41, 41. The fluid, as for example, mercury is drawn from the felt roll housing 14 by the suction pipe 42 to the pressure pump 43, operated by the motor 44, and is forced through the pipe 45, into the nozzles 41, 41. As the mercury or similar material passes through the restricted area 13, it is moving with considerable velocity, which velocity is reduced as the portions of increased area 46 are reached. The restricted area connected with the passage of large areas forms a Venturi type nozzle.

In this form of my invention the liquid of the seal is forced through the restricted area 13 of the passage with just sufficient velocity to balance the pressure of the atmosphere upon the seal, which pressure, if not counteracted, would cause the fluid of the seal to back up within the vacuum chamber.

The drying drums or cylinders 2, 3, 4, 5 and 6 are all preferably driven at the same speed that the web is traveling and are heated by steam in any suitable manner.

The felt dryers 17, 22 and 25 are also heated by steam or other suitable means so as to dry the felts passing over them.

In some cases I may use a combination of the velocity fluid vacuum seals shown in Figs. 2 and 3 and in Fig. 1. I have shown such a construction in Fig. 4, in which the

felt roll chamber or housing 11 is connected with the vacuum chamber 1 by means of a passage having a restricted area 13. Connected with this restricted passage are nozzles 48, 48, through which the mercury or similar material taken from the barometric seal 30 by means of the suction pipe 33 is forced by the pump 34, operated by the motor 35. In this form of my invention, the mercury is forced through the nozzles 48, 48 and then through the restricted passage 13 at considerable velocity. This velocity decreases as the liquid reaches portions of greater area 49. This passage is in effect a Venturi type nozzle. The surplus fluid then passes through the overflow pipe 37 back into the barometric seal 30. Should any of the sealing fluid work past the nozzles 48, 48 it cannot back up in the vacuum chamber, for it will pass through the pipe 31 into the barometric seal 30. The fluid of the seal can be withdrawn at any time by removing the plug 50. In this form of my invention the velocity of the fluid through the openings or nozzles 48, 48 and the Venturi nozzle, formed by the restricted passage 13 and progressive portions of increased area 49, will not be as high as the velocity of the fluid through the form of my invention shown in Fig. 3. In Fig. 3 the velocity must be such as to equal or exceed the atmospheric pressure upon the surface of the seal, to prevent any of the fluid backing up into the vacuum chamber. In the form of my invention shown in Fig. 4 the velocity can be reduced below that shown in the other figure, for if the atmospheric pressure does cause any of the fluid to flow into the vacuum chamber it will be immediately withdrawn by means of the barometric seal.

In all forms of my invention the restricted passage is wide enough to accommodate the widest web of paper or sheet material to be dried. The passage is made as restricted as possible to accommodate the web, and the felts should they be used, and to reduce the amount of work thrown upon the pump.

I have shown another modification of my invention in Fig. 5, in which the vacuum chamber 1 is connected with the felt roll housing 11 by a restricted passage 51. This passage is provided with a plurality of nozzles 52, 52, 53, 53, 54, 54. Mercury or similar material is forced through the nozzle 52, 52 by means of the pump 55, which gets its supply from the barometric seal 56, through the suction pipe 57. The nozzles 53, 53 are supplied by the pump 58 from the barometric seal through the pipe 59, and the nozzles 54, 54 are supplied by the pump 60 from the barometric seal through the suction pipe 61. The mercury passes through the restricted area 51 with

considerable velocity until it reaches the section of larger area 62 where its velocity will be decreased. The restricted passage 51 with its portion 62 of larger area is in effect 5 a Venturi nozzle. It then passes under the felt roll 10 into the pipe 63 and back to the barometric seal 56. Should the velocity of the mercury through these different nozzles 52, 53 and 54 not be sufficient, on any particular 10 adjustment of the pumps, to prevent some of the mercury working back into the vacuum chamber 1, this mercury is caught in the well 64 and passes through the pipe 65 back to the barometric seal 56. The end 66 of 15 the pipe 65 is mounted below the level of the suction pipes 57, 59 and 61 so that it will be impossible to break the vacuum in the vacuum chamber by speeding up the pumps 55, 58 or 60. These pumps are all run by 20 one motor 67 through a shaft 68 and gearing 69. Of course they may be operated by separate motors if desired.

In Fig. 6 I have shown a further modification of my invention in which I employ 25 a plurality of nozzles and restricted areas connected in series.

In this form of my invention the interior of the vacuum chamber 1 is connected with the felt roll housing 11 with a passage 75, 30 and provided with different sets of nozzles 76, 77 and 78, and different restricted areas and enlarged areas all connected in series.

The mercury or similar material is taken from the barometric seal 56 by the suction 35 pipe 79 and is pumped by the pump 80 through the nozzles 76. The fluid has considerable velocity as it passes through the restricted area 81, its velocity falling as it reaches the portion 82 of larger area. The 40 suction pipe 83 of the second pump 84 is connected with the larger area 82 and gets its supply from that area. It then pumps the fluid through the nozzles 77 and the second restricted area 85, the velocity of the 45 fluid again decreasing as it reaches the second large area 86. The suction pipe 87 of the third pump 88 is connected with the large area 86 and pumps the fluid through the nozzle 78, the fluid then passing through 50 the third large area 89 into the felt roll housing 11. The pumps may be driven in any suitable manner. I have shown them driven, for example, by the motor 90 through the common shaft 91. The pipe 55 63 connects the felt roll housing 11 with the barometric seal 56.

While I have shown three sets of nozzles and restricted and enlarged areas, for purpose of illustration, it is of course to be understood that any number desired may be used.

While I preferably use mercury as the fluid of my velocity fluid seals shown in Figs. 1 to 6 inclusive it is of course to be understood that the liquid might be an amal-

gam or any other suitable material having no affinity for the web treated and no deleterious effect upon it. It is also, of course, to be understood that the vacuum chamber 100 of Fig. 7 may be equipped with one or 70 more, drying drums or cylinders such as 2, 3, 4, 5 and 6.

Instead of arranging my velocity fluid seal horizontally as shown in Figs. 1 to 7 inclusive, I may arrange it at any suitable angle 75 to the horizontal, in which case there will be more or less static head. In Fig. 8 I have shown my velocity fluid seal at right angles to the horizontal.

In this figure the felt roll housing 110 is 80 connected with a vertical passage 111 having a restricted area 112. This passage 111 opens into the vacuum chamber 113 within which are mounted one or more drying drums or cylinders 114.

If mercury or other similar material be used as the fluid of my seal it will fill the felt roll housing 110 reaching the level 115 on the surface exposed to the atmosphere and the level 116 in the passage 111. The height 90 in the passage of course will depend on the degree of vacuum in the vacuum chamber 113.

The mercury or similar material forming the fluid of the velocity fluid seal passes 95 through the restricted area 112, and through the pipe 117 into the barometric seal 118. The suction pipe 119 of the pressure pump 120 withdraws the fluid from the barometric seal 118 and is arranged as described in the other figures so as not to break the barometric seal. The pressure pump 120 is driven in any suitable manner, as by the motor 121, and forces the fluid through the pipe 122 and into the felt roll 105 housing 110.

The height of the column of mercury or similar material in the passage 111 may be varied. Assuming, for example, that the vacuum maintained in a vacuum chamber 110 is 28 inches of mercury, and the column of mercury, in the passage is 18 inches, this column of mercury or similar material acts as a static head and will lessen the amount of fluid which will have to be pumped by 115 the pump 121.

With the apparatus arranged as above described the 18 inches of mercury or similar material balances 18 inches of vacuum in the vacuum chamber 113. As the vacuum maintained therein is, for example, 28 inches, there will be a difference of only 10 inches which will have to be overcome or compensated for by the pump 120 pumping the fluid through the restricted passage 112 125 and around through the barometric seal 118, suction pipe 119, pressure pump 120 and pipe 122. In other words the pump instead of pumping the fluid at a velocity sufficient to overcome a vacuum of 28 inches 130

of mercury will, with this static head of 18 inches, only have to pump the fluid of the seal at a sufficient velocity to overcome a vacuum of 10 inches of mercury. Of course, different degrees of vacuum, and different static heads may be employed without departing from my invention. It is of course to be understood that any of the other types of seals shown in other figures of the drawings can be arranged at an angle to the horizontal, or vertically, as shown in Fig. 8.

My method possesses many advantages not present in processes heretofore used for many years in the drying of paper.

The evaporation process, which is characteristic of the so-called loft drying of paper, has many fully recognized disadvantages, and yet it is used today and has been in use for many years. In this method the wet paper is taken from the paper machine, cut into sheets, hung on poles, carried to the drying room where it is subjected to hot air at about 130° F. for about 48 hours, and when dry, each sheet is separately calendered. Although possessing the advantage of drying at a comparatively low temperature, whereby the moisture is slowly evaporated, loft drying is obviously very inefficient and costly, because it requires many separate manipulations, is extremely slow, uses extensive floor space and wastes heat.

The process which is employed in the ordinary paper machine in common use, is likewise subject to many disadvantages. In such machine, the wet paper as it comes from the paper machine, is passed over many revolving cylinders, heated internally by steam to sufficiently high degree of heat, to raise the temperature of the water in the paper to 212° F., the atmospheric boiling point of water. It is customary to supply the drying cylinders with steam at approximately 5.3 pounds gauge pressure, at which the steam has a temperature of 228° F., giving a difference of temperature (228°—212°) of only 16° F. With this slight difference of temperature the transfer of heat is extremely slow, and hence it is necessary to employ many drying cylinders, in board machines often one hundred, and in news print machines, forty or more.

Also due to convection and conduction losses, as well as those incident to leaks in the piping system and other inefficiencies, the heat actually required for atmospheric drying of a ton of wet paper, is very much in excess of the theoretical requirement. The thermal efficiency of atmospheric drying by steam heated cylinders is therefore very low. Furthermore, the steam produced from boiling the water out of the paper is driven off into the operating room,

and although fans and exhausters are employed, at large expense for power and maintenance, the room atmosphere is so constantly saturated with moisture as to rust and ultimately destroy all iron and steel materials, and produces an exceedingly disagreeable and unhealthy atmosphere in which to work. It is well known that the minimum temperature 212°, the atmospheric boiling point of water, is positively injurious to, and results in oxidizing, the fibres of the paper, the strength of which is vastly improved when the paper is dried at lower temperature, as in loft drying. This atmospheric drying process requires large initial cost for cylinders, felts, and other necessary equipment, and extensive floor space, and results in the consumption of large amounts of power, and great cost for operation, maintenance and repairs.

Some of the modern open air dryers are equipped with a blower system by which air, either heated or not, is blown through the dryer section, which will lower the temperature at which the water is evaporated from the paper much below 212° F. and may, in some cases, reduce the temperature of evaporation as low as 180° F. or lower.

In my improved vacuum drying method I contemplate maintaining within the chamber a vacuum of about 28" of mercury, in which water boils at 100° F., and supplying the drying cylinders with steam at 5.3 pounds gauge pressure, producing a temperature of 228° F. The temperature difference between the temperature of the steam in the cylinders and that of the paper, is therefore, 128° F. in my vacuum method, or 8 times greater (16° $\times$ 8=128° F.) than the temperature difference in atmospheric drying. In my improved method the paper dries approximately 8 times faster than in atmospheric drying, and I require only about one-eighth the number of drying cylinders to dry paper at the same rate of speed. I am able to dry paper with 5 cylinders in the same time required of 40 cylinders drying at atmospheric pressure, resulting in great economies in cost of the machine, floor space and of necessary piping, felts, auxiliary equipment, and particularly in power and maintenance charges.

The thermal efficiency of my vacuum method is very much greater than that of the atmospheric cylinder drying heretofore in universal use for drying paper. Theoretically, it requires about 5287 pounds of steam to dry one ton of paper at atmospheric pressure, but to compensate for convection and conduction losses, and those due to leaks in the piping system, and other inefficiencies, it has been shown in practice that about 10,600 pounds are required.

In my method, using a vacuum of about

28", the convection, conduction and piping losses are exceedingly small and the total steam required to dry a ton of paper by my method is approximately 5200 pounds.

5 It is an established fact that paper dried at low temperatures is much stronger than when it is dried at the high temperatures used in paper machine atmospheric drying. Paper dried in a vacuum of 28", or at a 10 temperature of about 100° F., as in my method, is very much stronger than paper dried at atmospheric pressure, when the steam in the dryers is at 228° F. When paper is dried by my method, therefore, a 15 cheaper furnish or stock can be used and still produce a paper equal in strength to atmospheric dried paper, in which a higher grade furnish or stock is used. In making newsprint paper, I am able to dispense 20 with a considerable portion of the more expensive sulphite pulp, as this can be replaced with the cheaper ground wood pulp. By my method I also reduce the number 25 of breaks in the web as it passes over the cylinder.

Furthermore, in my method there is a great saving of heat (or steam) because the process is carried on in a vacuum chamber which acts on the principle of a thermos bottle, and the steam and vapors driven out of the wet paper are caught in the closed vacuum chamber, and conducted away to the condenser. The operating room is free from steam, humidity and 30 heat, and fans, and exhausters are dispensed with. In the use of my method the apparatus is at all times operating under definite humidity, the control of the drying 35 can be closely standardized, and the moisture content in the paper carefully regulated.

Having pointed out the many advantages 40 of my method and apparatus over those heretofore used, it will be apparent that the use of my invention results in great economy in the initial cost of apparatus and in large savings in cost of operation, maintenance and repairs.

45 By the terms "velocity fluid seal" or "velocity fluid seals" as used in this application, I mean any moving fluid seal, sealing the opening or openings of the vacuum chamber, and flowing into, or out of, the vacuum chamber, or tending to flow into 50 or out of the vacuum chamber, and through which the material to be treated is passed in any suitable manner.

Having thus described this invention in connection with different illustrative embodiments thereof, to the details of which I do not desire to be limited, what is claimed as new and what is desired to secure by Letters Patent is set forth in the appended claims.

60 65 What I claim is:—

1. The method of sealing a vacuum chamber having an opening for the admission of material into said vacuum chamber to be treated consisting in preventing admission of air through said opening by sealing said opening with a fluid through which the material to be treated passes into the vacuum chamber, and causing said fluid to flow.

2. The method of sealing a vacuum 75 chamber having openings for the admission of material to be treated into and out of said vacuum chamber, consisting in preventing the admission of air through said openings by sealing said openings with a 80 fluid through which the material passes into and out of the vacuum chamber, and causing said fluid to flow.

3. The method of continuously passing 85 sheet material into and out of a vacuum chamber consisting in continuously feeding it into and out of a vacuum chamber through a fluid which prevents air getting into the vacuum chamber, and causing said fluid to flow.

4. The method of continuously passing 90 sheet material into and out of a vacuum chamber consisting in continuously feeding it into and out of a vacuum chamber through liquid seals, causing said liquid to 95 move in the direction of travel of the sheet material thereby preventing air getting into the vacuum chamber.

5. In a vacuum apparatus the combination 100 of a vacuum chamber provided with one or more openings for the admission and withdrawal of material to be treated into and from said vacuum chamber, and one or more velocity fluid seals protecting said opening or openings and preventing the admission of air into said vacuum chamber.

6. In a vacuum apparatus the combination 105 of a vacuum chamber provided with one or more openings for the admission and withdrawal of material to be treated into and from said vacuum chamber, and one or more velocity fluid seals protecting said opening or openings and preventing the admission of air into said vacuum chamber and means to collect the fluid of the seal.

7. In a vacuum apparatus the combination 110 of a vacuum chamber provided with one or more openings for the admission and withdrawal of material to be treated into and from said vacuum chamber, and one or more velocity fluid seals protecting said opening or openings and preventing the admission of air into said vacuum chamber and again deliver the same to the velocity 115 fluid seal.

8. The method of continuously drying a web of wet paper consisting in continuously feeding it into and out of a vacuum chamber through velocity fluid seals, and drying 120 said web while in the vacuum chamber.

9. The method of continuously drying a web of wet paper consisting in continuously feeding the web into and out of a vacuum chamber through mercury, amalgam or similar material causing said mercury or similar material to move, and drying said web in said vacuum chamber.
10. The method of sealing a vacuum chamber having an opening for the admission of material into said vacuum chamber to be treated consisting in preventing the admission of air through said opening by permitting a sealing medium to flow through said opening into the vacuum chamber and removing said sealing medium from said vacuum chamber.
11. The method of sealing a vacuum chamber having an opening for the admission of material into said vacuum chamber to be treated consisting in preventing the admission of air through said opening by permitting a sealing medium to flow through said opening into the vacuum chamber and removing said sealing medium from said vacuum chamber and again using the removed sealing medium by permitting it to flow through said opening.
12. In a vacuum apparatus the combination of a vacuum chamber having one or more restricted passages through which the material to be treated is passed, means to supply a sealing liquid through said restricted passage or passages, said sealing liquid sealing the vacuum chamber and passing into the vacuum chamber with the material to be treated, and means to withdraw said sealing fluid from the vacuum chamber.
13. In a vacuum apparatus the combination of a vacuum chamber having one or more restricted passages through which the material to be treated is passed, means to supply a sealing liquid through said restricted passage or passages, said sealing liquid sealing the vacuum chamber and passing into the vacuum chamber with the material to be treated, and means to withdraw said sealing liquid from the vacuum chamber, and again deliver the same to said one or more restricted passages to be again used.
14. In a vacuum apparatus the combination of a vacuum chamber provided with one or more openings for the admission and withdrawal of material into and from said vacuum chamber to be treated, and one or more liquid seals flowing into the vacuum chamber through said opening or openings and preventing the admission of air into the vacuum chamber and means to withdraw said liquid from the vacuum chamber.
15. In a vacuum apparatus the combination of a vacuum chamber provided with one or more openings for the admission and withdrawal of material into and from said vacuum chamber to be treated, and one or more liquid seals flowing into the vacuum chamber through said opening or openings and preventing the admission of air into the vacuum chamber and one or more barometric seals to withdraw said liquid from the vacuum chamber.
16. The method of sealing the entrance and exit openings of a vacuum chamber through which a wet web of paper is fed, said method consisting in feeding the web of wet paper and a liquid into and out of the vacuum chamber, the liquid sealing the openings.
17. The method of sealing the entrance and exit openings of a vacuum chamber through which a wet web of paper is fed, said method consisting in feeding the web of wet paper and a liquid into the vacuum chamber, the liquid sealing the openings, and withdrawing the fluid from the vacuum chamber.
18. The method of sealing the entrance and exit openings of a vacuum chamber through which a wet web of paper is fed, said method consisting in feeding the web of wet paper and mercury, amalgam or similar material into the vacuum chamber, the mercury, amalgam or similar material sealing the openings.

OGDEN MINTON.
